UNITED STATES PATENT OFFICE.

LEE HUGHES, OF MARSHALL, MISSOURI.

ELECTRIC BELT.

SPECIFICATION forming part of Letters Patent No. 325,086, dated August 25, 1885.

Application filed April 13, 1885. (No model.)

To all whom it may concern:

Be it known that I, LEE HUGHES, a citizen of the United States, residing at Marshall, in the county of Saline and State of Missouri, have invented certain new and useful Improvements in Electric Belts, of which the following is a specification, reference being had therein to the accompanying drawings.

This invention relates to certain improvements in electric belts and other similar articles, and it has for its objects to so construct the connections of the plates constituting the battery that greater and more perfect conductive power will be obtained, and corrosion and destruction at the point of connection will be in a great measure, if not entirely, obviated, and also to provide for an improved construction of belt proper, whereby it may be more conveniently used, and made more comfortable to the wearer, as more fully hereinafter specified. These objects I attain by the means illustrated in the accompanying drawings, in which—

Figure 1 represents an elevation of the belt with a portion broken away, showing the enclosed battery; Fig. 2, a detached view of two of the battery elements detached, showing the connecting conductors.

The letter A indicates the belt proper, which is constructed of any suitable water proof material, such as rubber cloth, oiled silk, or the like, or a suitable fabric, lined with such material. The said belt is made of double thicknesses of material, so as to form an interior space for the battery, which is indicated by the letter B in the drawings. The said battery is composed of a series of sections composed of zinc and copper plates, (indicated by the letters *a b*,) between which are interposed absorbent or porous separating material *c*, which may be felt or other suitable substance. The parts composing said sections are bound together by means of cords or bands of suitable non-conducting material, as indicated by the letter *d*.

The letter *e* indicates the connecting-conductors, which are composed of strands of twisted wire passing alternately through the zinc and copper plates of the sections at the ends, being twisted or tied between the plates, in order to securely connect the whole together.

The extremities of the wires are spread out so as to form brushes, which bear against the respective plates of each section, as plainly shown in Fig. 2, for the purpose more fully hereinafter explained. The end conductors are soldered or otherwise securely attached to the metallic disks or pads *C*, which are fastened to the belt near the ends, as shown in Fig. 1 of the drawings. The said end conductors are attached one to the zinc and the other to the copper terminal plates of the battery, the disks being thus made to serve as the positive and negative poles of the same. To the inside of the belt near each disk is arranged a flap, *D*, of linen, cotton, or other suitable material, which may be folded over the disks, to modify or weaken the action of the current, and prevent direct contact of the metal with the body, which is in many cases disagreeable. The said flaps, it is evident, must be of some water-absorbent fabric, in order to render it conductive material, so as to permit of the passage of the electric current. The belt is provided with the usual strap, *E*, at one end and with a buckle (not shown) at the other.

The operation of my invention will be readily understood in connection with the above description, and is as follows: The sections being arranged as shown in Fig. 1 of the drawings, and the absorbent separating material between the plates saturated with acidulated water or other exciting solution, the battery is arranged within the belt, and the connections with the disks, after which the belt is closed, and is ready for use. By means of the connecting-conductors, which are formed with brushes bearing upon the plates of the battery-sections, and held against the same by the casing or envelope of the belt, which presses the whole firmly together, it will be seen that the current passes from one plate to another at numerous points. This causes the zinc plates to decompose uniformly throughout, preventing corrosion at the point of contact or connection of the conductors, which would otherwise be destroyed at such points long before the entire plates were consumed, allowing them to break apart and render the battery useless. It will thus be seen that by my improved connecting-conductors a battery may be formed which will be cheap in con-

struction, and economical in use, as it will not break apart or cease to act until the zinc plates are entirely consumed.

Another advantage of my improved belt is that the disks, being provided with covering-flaps, will not prove disagreeable or inconvenient to the most delicate person, which is a great desideratum.

Having thus described my invention, what I claim, and desire to secure by Letters Patent, is—

1. The combination, in a battery for electric belts or other like purposes, of the positive and negative plates or elements, and the connecting-conductors having brushes at their extremities bearing upon the connected plates, substantially as and for the purposes specified.

2. The combination, with the belt, of the battery connected in sections by the connecting-conductors, having brushes at their extremi-

ties and the metallic disks or pads connected to the terminal conductors, substantially as and for the purposes specified.

3. The combination, with the belt proper, the battery, and the metallic disks or pads, of the flaps adapted to cover said disks or pads, substantially as specified.

4. A conductor for connecting the zinc and copper plates of a battery for electric belts, consisting of strands of wire, twisted together between their ends, and having said ends spread apart in the form of brushes, substantially as and for the purposes set forth.

In testimony whereof I affix my signature in presence of two witnesses.

LEE HUGHES.
